[57] CLAIM

The ornamental design for a watermelon plate, as shown and described.

DESCRIPTION

FIG. 1 is a top plan view of a watermelon plate showing my new design;

FIG. 2 is a side elevational view thereof, the opposite side being a mirror image thereof;

FIG. 3 is a fragmentary sectional view taken on line 3—3 of FIG. 1;

FIG. 4 is a bottom plan view; and

FIG. 5 is an exploded side elevational view thereof.

FIG. 4

FIG. 5
